WILLIAM SEARS WHITE, OF DENVER, COLORADO.

FLUSHING VALVE.

Application filed July 17, 1923. Serial No. 652,126.

REISSUED

To all whom it may concern:

Be it known that I, WILLIAM SEARS WHITE, a citizen of the United States of America, and a resident of Denver, in the county of Denver and State of Colorado, have invented a new and Improved Flushing Valve, of which the following is a description.

My invention relates to flushing valves and more particularly to that type of valve including a float piston movable in a vertical cylinder and in which manually operated means is provided at the exterior of the valve to give rocking movement to a shaft to cause the piston to be displaced to admit the flushing water.

The general object of the present invention is to improve in various particulars valves of the indicated type with a view to promote simplicity, attain increased efficiency, and provide a novel means for variously regulating the flushing period.

The nature of the invention, its distinguishing features and advantages, will clearly appear as the description proceeds.

Reference is to be had to the accompanying drawings forming a part of this specification, it being understood that the drawings are merely illustrative of practical examples of the invention.

Figure 1 is a side elevation of a flushing valve shown partly broken away and part of a discharge pipe being shown in vertical section;

Figure 2 is an enlarged vertical section of the valve and part of the flushing tank;

Figure 3 is a horizontal section on the line 3—3, Fig. 2;

Figure 4 is a vertical section of the valve in a slightly modified form;

Figure 5 is a fragmentary vertical section showing a further slight modification;

Figure 6 is a detail of the upper portion of the piston showing a modification;

Figure 7 is a fragmentary horizontal section in the plane indicated by the line 7—7, Figure 6.

In the illustrated example of my invention the numeral 10 indicates a flushing tank mounted in which is a valve casing 11, the lower end of which has a chamber 12

rigid therewith and disposed below the bottom of the tank 10, said chamber 12 having threaded connection with a discharge pipe 13. The casing 11 has inlets 14 near the bottom thereof to permit water to the interior of the casing. A float piston 15 is vertically movable in the casing 11 and adapted to seat on an annular flange 16 at the base of the casing 11. Journaled in the chamber extension 12 is a rock shaft 17 having a laterally bent handle 18. On the rock shaft 17 is a lateral arm 19 extending into the chamber 12 and secured to the lower end of a vertical pin 20. The pin 20 extends upwardly through bottom of the float piston 15. The piston 15 is provided with a tube 21 surrounding the upper end of the pin 20 and spaced therefrom. The sleeve 21 is slotted at its lower end as at 22 and near the upper end has holes 23. The space 121 between the tube 21 and pin 20 forms a passage for air and water as will appear.

Above the pin 20 the float valve 15 has a ball 24 at the top of which seats a ball valve or equivalent valve 25. Said valve has a chamber 26 beneath a cap 27 on the piston, in the top of the casing 11 in the construction shown in Figures 1 to 3. Near the top of the casing 11 is a spider or partition 28 affording a flow of air and water and above the partition is a cap 29 having a depending headed pin 30 movable in a ventral hole 31 of partition 28. The lower end of the piston 15 is closed by a hollow screw plug 32 through a hole 33 in which the vertical pin 20 has movement into the tube 21. In the chamber 26 is a second valve 34 controlling the upper end of vertical passage 25 in the bottom of the chamber 26 to establish communication between said chamber 26 and the chamber 111 or upper portion of the casing 11.

When the shaft 17 is rocked by its handle 18 the arm 19 will raise the pin 20 and lift the valve 25 from its seat, thereby opening the passage 121 and as the pin 20 continues to rise, it will lift the piston 15 off its seat 16 and move the piston into the chamber 111. As the piston 15 is raised, the water, displaced from the chamber 111, can pass through the passage 35 past the

valve 34 and when the chamber 26 and its valve 25 are raised, water will pass through the tube 21 and through the discharge pipe 13. Water permitted to pass through the 5 inlet slots 14 and thence to the discharge pipe 13, exerts a downward pull on the piston 15. As the piston descends it tends to create a vacuum in the chamber 111, which 10 vacuum is broken by the air within the hollow piston 15 being allowed to pass by the valve 25 and beneath the valve 34 through the passage 35 to chamber 111, it being understood that the valve 34 does not fit tightly on its seat but that a limited 15 passage is provided beneath the valve by the formation of the seat.

The downward pull of the water on the piston 15 finally seats the latter. The piston 15 is not tight in the casing 11 but permits the flow 20 of water from the inlet 14 between the piston and said casing to the chamber 111, producing a pressure and cushion in said chamber, tending to cause the piston to seat without producing a water hammer. After the 25 piston 15 is seated the water which has passed into the hollow piston 15 and displaced air while the piston is in operation, will escape through the slots 32 and hole 33 and the piston will again be filled with air so 30 that the valve is ready for another operation. The valve 34 acts as a trap to prevent the contents of the hollow piston from passing too freely into the chamber 111 and a predetermined flushing period can be had by 35 regulating the flow between the valve 34 and its seat. The loose cap 29 because of having limited vertical movement permits air to pass through the spider 28 and outward from the top of the chamber 111 to the top 40 of the tank 39 or to a supply pipe to finally pass, if desired, to auxiliary air storage chambers provided in connection with some forms of valves of this general type.

In the form shown in Figure 4 the casing 45 111 corresponds essentially with the casing 11, except that at its base below the inlet 114 the casing is formed integral with an outer housing or shell 110 to contain water, in lieu of the tank 10. Said housing 110 has 50 a cap 36 which secures the flanged lower end on an inlet pipe 37 leading into the top of said housing. The casing 111 and its appurtenances as well as the valve and its operating and controlling pin 20 are the same as 55 in the previously described construction except that the casing 111 above the loose cap 29 has an integral extension 38 communicating directly with the inlet pipe 37. Said inlet pipe 37 may lead from a tank or 60 supply pipe 39.

In the form shown in Figure 5 the construction is the same as in Figure 4 except that the cap 29 and pin 30 are omitted. Instead of the spider or partition 28, a closed 65 top 128 is provided on the casing 111. In the

constructions shown in Figure 4 and also in Figure 5 the extension 38 has lateral openings 40 above the casing which in Figure 5 is designated 211. Water may flow from the pipe 37 through the extension 38 70 and outwardly through the openings 40 to the space between the casing 111 and the housing 110, thence to the inlet 114.

In Figures 6 and 7 in lieu of the valve 34 and passage 35 an equivalent check valve 75 assemblage is provided, comprising an annular resilient band 134 controlling lateral openings 135 that establish communication between the chamber 126 corresponding with the chamber 26 whereby to control communication between the chamber 111 of casing 11 and the interior of the hollow piston 15 through the passage 221 corresponding with the passage 121.

I would state in conclusion that while the illustrated examples constitute practical embodiments of my invention, I do not limit myself strictly to the exact details herein illustrated, since, manifestly, the same can be considerably varied without departure 90 from the spirit of the invention as defined in the appended claims.

Having thus described my invention, I claim:

1. A valve of the class described comprising a casing having an inlet for water near its lower end, a hollow piston operating in said casing and formed with a separate chamber at the top of the piston, said piston having a passage establishing communication between the piston and the said chamber, a valve controlling said passage, a second valve controlled passage leading from said chamber to the interior of said casing, and manually operable means to displace the first-mentioned valve and cause the piston to rise in said casing above the said inlet.

2. A valve of the class described comprising a casing having an inlet for water near its lower end, a hollow piston operating in said casing and formed with a separate chamber at the top of the piston, said piston having a passage establishing communication between the piston and the said chamber, a valve controlling said passage, a second valve controlled passage leading from said chamber to the interior of said casing, and a manually movable pin extending upwardly through the bottom of the casing and adapted to displace the first-mentioned valve and cause the piston to rise in the casing.

3. A valve of the class described comprising a casing having an inlet for water near its lower end, a hollow piston operating in said casing and formed with a separate chamber at the top of the piston, said piston having a passage establishing communication between the piston and the said

chamber, a valve controlling said passage, rise in the casing; together with a tube in a second valve controlled passage leading the hollow piston surrounding said pin and from said chamber to the interior of said casing, and a manually movable pin extending slotted at its lower end, the lower end of 10 the piston having a hole for the inflow and 5 upwardly through the bottom of the casing and adapted to displace the first- outflow of water. mentioned valve and cause the piston to
